United States Patent Office

Des. 231,672
Patented May 21, 1974

231,672

AUTOMOBILE

Gianpaolo Boano, Turin, Italy, assignor to Fiat Societa
per Azioni, Turin, Italy

Filed Aug. 9, 1971, Ser. No. 170,420

Claims priority, application Italy Feb. 19, 1971

Term of patent 17 years

Int. Cl. D12--08

U.S. Cl. D12--91

FIG. 1

FIG. 2

FIG. 3

FIG. 4

FIG. 1 is a perspective view of an "automobile" showing my new design;

FIG. 2 is a right side elevational view, the opposite side being substantially a mirror image thereof;

FIG. 3 is a front elevational view, it being understood that the pattern shown in the corners of the grille panel covers the entire surface of said panel;

FIG. 4 is a rear elevational view; and

FIG. 5 is a top plan view thereof.

I claim:

The ornamental design for an automobile, as shown.
